Primary Examiner — Karen E Kearney(74) *Attorney, Agent, or Firm* — Banner & Witcoff, Ltd.(57) **CLAIM**

The ornamental design for an electronic data module, as shown and described.

DESCRIPTION

FIG. 1 is a perspective view of an electronic data module showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken line showings of various electrical connectors and a peripheral notch are for the purpose of illustrating portions of the electronic data module and form no part of the claimed design.
